UNITED STATES PATENT OFFICE

FRIEDRICH W. F. BERGER, OF BERLIN, GERMANY, ASSIGNOR TO THE NATIONAL CASH REGISTER COMPANY, OF DAYTON, OHIO, A CORPORATION OF MARYLAND

CASH REGISTER

Application filed July 20, 1927, Serial No. 207,248, and in Germany August 11, 1926.

This invention relates to improvements in cash registers, and is shown applied to the type shown and described in Letters Patent of the United States, No. 1,619,796 issued to 5 B. M. Shipley on March 1, 1927.

One object of this invention is to provide novel means for preventing the insertion of a slip into the machine when the machine is adjusted to take one impression to be made 10 only on a detail strip which remains in the machine, thereby preventing the taking of the impression intended for the detail strip, on an inserted slip.

Another object is to provide novel mechanism for opening the slip receptacle when the machine is adjusted to take two impressions; one of which is made on the inserted slip and the other on the detail strip retained in the machine.

20 With these and incidental objects in view, the invention consists of certain novel features of construction and combinations of parts, the essential elements of which are set forth in appended claims and a preferred 25 form or embodiment of which is hereinafter described with reference to the drawings which accompany and form part of this specification.

30 Of said drawings:

Fig. 1 is a detail view showing the insertable slip receptacle and the device for normally preventing insertion of a slip, together with the novel mechanism for removing the 35 device from the slip receptacle opening.

Fig. 2 is a fragmentary detail view of the slip table, together with a portion of the device for normally preventing the insertion of a slip.

40 Fig. 3 is a detail view of the first transaction bank, and shows the mechanism operated by the list key for removing the device from the path of an insertable slip.

45 Fig. 4 is a diagrammatic view of the keyboard arrangement.

Fig. 5 is a detail view of the total lever showing its connection with the cam for operating the device which normally lies in 50 the path of a slip.

General description

In machines of the type to which this invention is shown applied, the upper printing hammer (the one shown in the present disclosure) is adapted to be controlled to take either one or two impressions. In either case, one impression must be made on the detail strip which remains in the machine. This is to insure a permanent record of every 60 transaction. When two impressions are taken, the first is taken on a check which is automatically ejected from the machine immediately after the impression is made. The second impression is then taken on the detail strip. Such is the case in the Shipley 65 patent above referred to.

The present disclosure does not contemplate the issuing of a check, by this mechanism, but is adapted to receive a slip inserted 70 by hand. Upon operation of the machine, the slip receives the first impression and is then ejected from the machine by the ejecting mechanism disclosed in said Shipley patent. The second impression is then taken, as 75 usual, on the detail strip.

The present case discloses mechanism which prevents the insertion of a slip for operations wherein the hammer makes only one impression, and enables such insertion 80 for operations wherein the hammer makes two impressions. Thus it is not possible for the operator to insert a slip for an operation wherein only one impression is made, and thus prevent the recording of this transaction on the detail strip.

When the present mechanism is used in connection with the said Shipley patent, it is intended that the mechanism disclosed therein to control the upper impression hammer for one or two operations be suitably notched so that during adding operations, depression of only the list key will cause two impressions, and so that during totaling operations only a moving of the total lever to 90 the reset position for the first transaction bank will cause two impressions. To so notch this mechanism is but a matter of choice, as will be apparent upon an understanding of the mechanism of said patent.

With the impression hammer so controlled, it becomes necessary to prevent the insertion of a slip at all times except when the machine is to add with the list key depressed, or is 5 to reset a totalizer controlled by any of the keys in the first transaction bank. The mechanism for preventing a wrongful insertion is fully set out in the detailed description, to follow.

10

Printer mechanism

The machine is provided with a plurality of type carriers 30 loosely mounted on a rod 31 (Fig. 1). Each type carrier is differentially adjusted under the control of an amount key or transaction key in the well known manner as is shown and described in the above mentioned Shiple patent. A printing hammer 32 is provided, adapted to 20 take one or two impressions from the type carrier 30, as controlled by the transaction keys and by the total lever. The means for effecting this control are not shown, and for a description and illustration of said means, 25 see the above mentioned patent.

A detail strip 33 is guided around the impression hammer by two rollers 34 and a plate 35. The machine is so constructed that when the impression hammer receives but 30 one operation, the impression will be taken on the detail strip 33, and when it receives two operations, two impressions will be made, one on the detail strip 33 and the other on an 35 insertable slip. Thus, an impression will be taken on the detail strip during each operation of the machine, and on the inserted slip only during those operations in which a slip can be inserted in the machine.

A slip table 36 is provided upon which the 40 insertable slip is placed when an impression is to be taken thereon. The cabinet 37 is formed with an opening 39 through which the slip can be inserted, a guide flange 38 facilitating such insertion. A strip is 45 wrapped around a shaft 41 to form a sleeve 67 having a lip 40 normally obstructing the opening 39 so that no slip can be inserted into the receptacle. The sleeve 67 is secured to and adapted to be operated by an arm 42, as 50 will be hereinafter described, when the list key 43 (Figs. 1 and 3) is depressed.

The list key 43 is slidably mounted in the key frame 44 carried by two rods 45. The 55 key 43 is provided with a pin 46 adapted to engage a cam edge 47 of an arcuate bar 68 secured to an arm 48 pivoted on a rod 66. Depression of the key 43 by the pin 46 co-operating with the cam edge 47, moves the bar 68 60 upwardly, thereby rocking the arm 48 clockwise. A link 50 pivoted to the arm 48, is also connected to a pin 69 carried by arms 49 and 52 (Fig. 1) pivoted on a shaft 53 supported by the side frames (not shown) of the machine. The arms 49 and 52 are connected by

a yoke or bar 70, to move in unison. These arms 49 and 52 also carry a ball-headed pin 51 engaged by an arm 54 secured to a shaft 55 carried by the frames 56 and 57. Also secured to the shaft 55 is an arm 58 provided with a stud 59, which cooperates with an arm 60 loosely pivoted on the shaft 55. The arm 60 is connected to a bell crank 61 by a link 62. The arm 60 is normally held against the stud 59 by a spring 63. The bell crank 61 is loosely pivoted on a rod 64 and is connected to the arm 42 by a link 65.

From the above it can be seen that when the list key 43 is depressed, and the arms 48, 49 and 52 are rocked clockwise, the arm 54, shaft 55 and arm 58 are rocked clockwise, thus moving the arm 60 clockwise. The clockwise movement of the arm 60, through the link 62, transmits clockwise movement to the bell crank 61 thereby raising the link 65, which rocks the arm 42 and moves the lip 40 upwardly from the opening 39 to enable a slip to be inserted in the machine.

The lip 40 has two lugs 75 (Figs. 2 and 3) which project into slots cut into the slip table 36. In this manner the opening 39 is obstructed and no slip can be inserted into the machine until after the list key has been depressed, whereupon the lip 40 and the lugs 75 will be raised to permit the slip to be inserted, as before described.

The arm 48 is held in its normal position, with a finger 71 thereof contacting a stationary stud 76, as shown in Fig. 3, by a spring 74 (Fig. 1) connected to an arm 73 rigid with the arm 58 which, it will be recalled, is secured to the shaft 55.

It will be seen by referring to Fig. 3, that the bar 68 is provided with radial slots 77 opposite pins 78 of each of the department keys 79. From this it can be seen that if any key in this bank is depressed, except the list key 43, the bar 68 will not be moved upwardly and therefore the lip 40 will not be raised above the opening 39. This machine is also provided with two additional banks of departmental keys 79 (Fig. 4) but since there is no bar, similar to the bar 68 adjacent to these banks, depression of any one of these keys will have no effect on the lip 40, and therefore when the machine is operated with any of the departmental keys 79 only, depressed, no slip can be inserted in the machine.

The machine is so constructed that if any one of the departmental keys 79 is depressed, the impression hammer 32 (Fig. 1) will receive only one operation, and therefore will take only one impression. Since no slip can be inserted when the machine is operated with one of the keys 79 only, depressed, it can be seen that the impression will always be made on the detail strip.

It can be readily seen that any one of the keys adjacent the bar 68 can be arranged to

operate said bar. The only modification necessary to accomplish this is to provide a cam edge 47 opposite the desired keys instead of the radial slots 77. Thus, any one or more of the keys in the control banks may be arranged to displace the lip 40 thereby permitting a slip to be inserted into the receptacle. However, for the purpose of illustration, only the "list key" is shown herein as being adapted to control the insertion of a slip. If any of the other keys should be so constructed, it would also be necessary to arrange to control the printing hammer so that two impressions would be made upon depression of any of these other keys.

The well known flexible detent 80 is provided for co-operating with the pin 46 of the list key and the pins 78 of the departmental keys 79 for holding them in their depressed positions. Each detent 80 is carried by a pair of arms 81 and is adapted to release the keys at the end of the operation of the machine, in the usual and well known manner.

Total control lever

Machines of this type are also provided with a total control lever 90 (Fig. 5) adapted to control the machine for total taking operations in the usual and well known manner. In the system herein disclosed, it is desired to print the total taken from any totalizer represented by keys in the first or right hand bank, on a slip. The first position below "add" (Fig. 4) is the position to which the total lever is adjusted when a total is to be taken from any of the totalizers represented by the keys in the first bank. Since any of these totals is to be printed on an inserted slip, it is necessary to not only open the receptacle by raising the lip 40 out of the path of the slip, but it is also necessary to control the machine so that the printing hammer will take two impressions.

The lip 40 is raised to permit insertion of the slip by a mechanism adjusted by the total lever, when it is moved to its first position below "add".

Pivoted to the total lever 90 (Fig. 5) is a link 95, also pivoted to an arm 96 secured to a spiral segment 97, loosely mounted on the shaft 53. The segment 97 meshes with a spiral gear 99 secured to a shaft 100 supported by the frames 56 and 57 and a bracket 101. Also secured to the shaft 100 is a cam 102 (Figs. 1 and 5). Co-operating with the cam 102 is a roller 103 carried by an arm 104 pivoted on a bracket 105. The upper end of the arm 104 is connected to the bell crank 61 by a link 106.

Movement of the total lever 90 to its first position below "add" will, by means of the connection just described, rotate the cam 102 counter-clockwise, (Fig. 1) thereby camming the arm 104 and link 106 toward the left. This movement of the link 106 will rock the

bell crank 61 clockwise and raise the link 65 to move the lip 40 high enough to permit the insertion of the slip.

The roller 103 is normally held in contact with the cam 102 by the spring 63 connected to the arm 60. The arm 60 is held in its normal position against the stud 59, thus holding the link 62 and bell crank 61 in their normal positions. The link 106, being connected to the bell crank 61 will therefore maintain the arm 104 in such position that the roller 103 will contact the cam 102 when the machine is at rest. However, when the list key is depressed and the bell crank 61 is rocked, the link 106 will rock the arm 104 and remove the roller 103 from the cam 102. But, when the machine comes to rest and the list key is released, the spring 63 will again return the parts to their normal positions in which the roller 103 is against the cam 102.

The cam 102 is so formed that the only time it will hold the arm 104 in its moved position, is when the total lever is in the first position below "add". If the total control lever is moved to any other of its six positions, the concentric portion of the cam 102 will be opposite the roller 103, and therefore the arm 104 will be left in its normal position as shown in Fig. 1. When said arm 104 is in this position the lip 40 prevents insertion of a slip into the machine.

While the forms of mechanisms herein shown and described are admirably adapted to fulfill the objects primarily stated, it is to be understood that it is not intended to confine the invention to the forms or embodiment herein disclosed, for it is susceptible of embodiment in various forms all coming within the scope of the claims which follow.

What is claimed is:—

1. In a machine of the class described, the combination of a receptacle to receive insertable slips, a pivoted lip normally preventing the insertion of a slip into the receptacle, a depressible key, a bar operable by said key, a bell crank, connections between the bar and the bell crank to operate the latter, a total control lever, a cam actuated by the lever, connections between the cam and the bell crank to operate the latter, and a link for transmitting the movement of the bell crank to the lip whereby the lip is moved into an ineffective position.

2. In a machine of the class described, the combination of a table to receive a slip to be printed upon; a shiftable obstructing device; lugs on the obstructing device adapted to project into openings in the table to normally prevent the insertion of a slip past the obstructing device; a machine-controlling manipulative device adapted to shift said obstruction device to enable a slip to be inserted past such device; and automatic means to project the lugs of the obstructing device

into the openings at the end of each operation of the machine.

3. In a machine of the class described, the combination of a receptacle, including a table to support insertable slips; a lip normally preventing the insertion of a slip; lugs on the lip adapted to normally project into openings in the table; a machine-controlling manipulative device; connections between said manipulative device and the lip to withdraw the lugs from the openings in the table, and to move the lip to permit the insertion of a slip; and automatic means, including a spring, to project the lugs on the lip into the openings in the table at the end of each operation of the machine.

4. In a machine of the class described, an entryway for a slip, an obstructing device adapted to prevent the insertion of the slip, means to move and hold the obstructing device in an ineffective position, and means to automatically return the obstructing device to effective position upon completion of a machine operation.

5. In a machine of the class described, an entryway for a slip, an obstructing device adapted to prevent the insertion of the slip, and means to move and hold the obstructing device in an ineffective position, the means including a shaft having a cam secured thereto, and a lever pivoted at one end to a stationary part of the machine and flexibly connected at its other end to an intermediate member, the latter being adapted to control the movements of the obstructing device.

6. In a machine of the class described, an entryway for a slip, an obstructing device adapted to prevent the insertion of the slip, a key, the depression of which is adapted to move the obstructing device to an ineffective position, and connections between the key and the obstructing device, including a shaft, an arm secured thereto, and a lever having a fixed pivot at one end and so associated with the free end of the arm, that movement of the arm will move the lever, but movement of the lever will not move the arm.

7. In a machine of the class described, the combination of a receptacle to receive insertable slips; means normally preventing the insertion of a slip into the receptacle; two manipulating devices for controlling the machine for various operations; and a mechanism adapted to be actuated on operation of either of said devices for moving said means to permit the insertion of a slip into said receptacle.

In testimony whereof I affix my signature.
FRIEDRICH W. F. BERGER.
